UNITED STATES PATENT OFFICE

115,101

DESIGN FOR AN ARTIFICIAL BAIT

George C. D olive, Winter Park, Fla.

Application March 10, 1939, Serial No. 83,505

Term of patent 7 years

To all whom it may concern:

Be it known that I, George C. D olive, a citizen of the United States, residing at Winter Park, county of Orange and State of Florida, have invented a new, original, and ornamental Design for an Artificial Bait, of which the following is a specification, reference being had to the accompanying drawing, forming a part thereof, in which:

Figure 1 is a plan view of an artificial bait showing my new design; Fig. 2, a side view in elevation; and Fig. 3, a front view in elevation.

I claim:

The ornamental design for an artificial bait, as shown.

GEORGE C. DOLIVE.
